US0D1031202S

(12) **United States Design Patent** (10) **Patent No.:** **US D1,031,202 S**
(45) **Date of Patent:** **** Jun. 11, 2024**

(54) **NESTABLE PALLET**

(71) Applicant: **Rehrig Pacific Company**, Los Angeles, CA (US)

(72) Inventors: **Jon P. Hassell**, Atlanta, GA (US); **Dane Gin Mun Kalinowski**, Foothill Ranch, CA (US)

(73) Assignee: **Rehrig Pacific Company**, Los Angeles, CA (US)

(**) Term: **15 Years**

(21) Appl. No.: **29/904,115**

(22) Filed: **Sep. 29, 2023**

(51) **LOC (14) Cl.** **09-08**

(52) **U.S. Cl.** USPC **D34/38**
